UNITED STATES PATENT OFFICE

JOHN B. FLYNN, OF DETROIT, MICHIGAN, ASSIGNOR TO TERNSTEDT MANUFACTURING COMPANY, OF DETROIT, MICHIGAN, A CORPORATION OF MICHIGAN

LOCK ASSEMBLY FOR VEHICLES

Application filed January 4, 1929. Serial No. 330,240.

This invention relates to a lock assembly for vehicles with a bolt adapted to be retracted against variant resistances.

In door lock assemblies for vehicles it is customary to provide a bolt which may be retracted in two ways, namely, automatically by the engagement of the bolt with the striker plate, or its equivalent, during the normal closing of the door and by retracting means operable either from without or within the vehicle.

It is the object of this invention to present a lock assembly with a bolt that can be retracted automatically by the cam engagement of the bolt head with the striker plate against a weak resistance and that can be retracted by retracting means operable from within or without the vehicle against a relatively strong resistance.

20 In the drawings:

Fig. 1 is an elevation of the lock assembly with parts broken away.

Fig. 2 is a section along the line 2—2 of Fig. 1.

25 Fig. 3 is a section along the line 3—3 of Fig. 1.

Fig. 4 is a detailed view of the retracting slide.

Fig. 5 is a detailed view of the latch bolt.

30 Referring more particularly to the drawings, the front plate of the lock will be referenced 1 and the face plate 2. Struck into the front plate are the guide lugs 3 for the reciprocable bolt 4. The face plate is provided 35 with a lock bolt opening 5, the sides of which also serve as guides for the bolt. Any suitable retracting means for the bolt may be provided. In this case I have provided a retracting means mounted on the front plate

40 and consisting of the spindle 6 upon which is mounted the handle 7 and the roll-back 8 which is adapted to slidably engage the roll-back abutment 9. Also fixed to the front plate as at 10 is the bolt spring 11 which is

45 adapted to resist the retraction of the retracting slide 12.

The lock bolt, as shown in Fig. 5, consists of the bolt head 13, the punched in semi-cylindrical spring chamber 14 and the lug 15.

50 The retracting slide 12 consists of the roll-

back abutment 9, the semi-cylindrical spring chamber 16 and the lug 17 against which the spring 11 is adapted to engage as at 18. The retracting slide is provided with an elongated opening 19, the sides of which are adapted for slidable engagement with the lug 15.

As shown in Fig. 2, the retracting slide is placed in slidable engagement with the lock bolt 4 so that the semi-cylindrical spring chambers 14 and 16 cooperate to form a cylindrical chamber for the spring 20. The front plate 1 has an opening 21 through which the semi-cylindrical spring chamber 14 of the lock bolt 4 projects, and which opening allows longitudinal movement of the portion 14 of the lock bolt.

Attached to the front plate is the rear latch frame 22 and the front latch frame 23 which has a lug 24 which serves as a guide member for the roll-back abutment 9. The operation of the latch bolt is as follows: While the door is being closed the lock bolt head 13 engages the striker plate or its equivalent. This cam engagement of the bolt head with the striker plate causes the bolt to be retracted against the action of the weaker spring 20 which is inclosed in the chamber formed by the opposed portions 14 and 16 of the bolt and retracting slide. Since the spring 20 lies free within the chamber formed by the portions 14 and 16 and since the lug portion 15 of the lock bolt is free to move in the opening 19 of the retracting slide 12, the bolt while being thus retracted, acts only against the spring 20. While the spring 20 is being retracted by the lock bolt, the retracting slide 12 is held stationary by the stronger spring 11.

When the lock bolt is retracted by the hand operating means, the operation is as follows: The roll-back 8 operating through the roll-back abutment 9 causes the retracting slide 12 to be retracted against the resistance of the bolt spring 11. The weaker spring 20 causes the lug 15 of the lock bolt 4 to hug the front side of the opening 19 in the retracting slide 12 as at 25. Hence, when the retracting slide is retracted, it positively engages the lug 15 and thereby causes the bolt 4 to be retracted.

From the above description it is evident that I have provided a door lock assembly with two springs of different strengths where-
in the weaker spring allows the door to close
easily, whereas the stronger spring is of suffi-
cient strength to bring the handle back to its
proper position.

Claims:

1. In a door lock, a reciprocable bolt ar-
10 ranged to engage a keeper and having a semi-
cylindrical portion, a slide having a semi-cy-
lindrical portion and adapted to slidably en-
gage said bolt, said semi-cylindrical portion
15 of the bolt adapted to cooperate with the semi-
cylindrical portion of the slide to form a
chamber, and resilient means in said chamber
for resisting relative movement between said
slide and said bolt, and resilient means of
20 greater strength for projecting said slide and
bolt whereby the bolt alone can be retracted
against the resistance of the weaker resilient
means and the bolt and slide against the re-
sistance of the stronger resilient means.
2. A latch comprising a frame, a bolt car-
25 ried by said frame having a plurality of rela-
tively slidable parts, a spring for holding said
parts in yieldable relation, retracting means
for the said bolt including a handle and roll-
back, a fixed stop for the said rollback, one
30 of said bolt parts yieldably abutting the said
rollback and another of said bolt parts being
arranged to engage a keeper, and a bolt spring
for projecting the said bolt whereby the roll-
back is held against the rollback stop and the
35 handle is held in a pre-determined position.
3. A latch comprising a frame having a
flange, a bolt carried by the said frame hav-
ing a plurality of relatively slidable parts, a
40 spring for holding said parts in yieldable re-
lation, retracting means including a rollback
and handle for the said bolt, the said latch
frame flange adapted to serve as a stop for
the said rollback, one of said bolt parts engag-
45 ing the said rollback and another of said
parts arranged to engage a keeper, and a bolt
spring stronger than the aforementioned
spring for projecting the said bolt whereby
the rollback is held yieldably against the
50 latch frame flange to hold the handle in a
pre-determined position irrespective of the
extent of the projection of said keeper engag-
ing part.
4. A latch comprising a frame, a composite
55 bolt carried by the said frame having a plu-
rality of relatively movable parts, one of said
parts having a bolt head adapted to interen-
gage a keeper and the other of said parts
adapted to operatively engage retracting
60 means for the said bolt, retracting means for
the said bolt, and a bolt spring stronger than
the aforementioned spring for projecting the
said bolt, the said stronger bolt spring at all
times exerting a positive pressure upon the
65 retracting means to move and maintain the
retracting means in a predetermined position

irrespective of the extent of projection of the
said keeper engaging part of the bolt.

In testimony whereof I have affixed my sig-
nature.

JOHN B. FLYNN.
